RING BOOK ASSEMBLING MACHINE

Edward F. Buenger, Oak Park, Ill., assignor to
Wilson-Jones Company, Chicago, Ill., a corpora-
tion of Massachusetts

Application February 1, 1934, Serial No. 709,317

8 Claims. (Cl. 153—10)

This invention relates to a ring book assembling machine particularly adapted to clinch tongues projecting from one book part against another part with which the first part is to be associated.

5 It is an object of this invention to provide simple and efficient means for securing ring metals to the back plate in the manufacture of ring books. It is a further object of this invention to provide such means that may be easily and quickly adjusted to work on any size binder and on any size ring metal. Other objects of this invention will become apparent upon reading the following description taken in conjunction with the accompanying drawings in which:

15 Figure 1 is a perspective view of the machine with a ring book in position with parts broken away to facilitate illustration of the structure;

Figure 2 is a longitudinal sectional view of the machine shown in Figure 1;

20 Figure 3 is a cross sectional view taken along the line III—III of Figure 2 looking in the direction of the arrows with the book removed; and

Figure 4 is a cross sectional view taken along the line IV—IV of Figure 2 looking in the direction of the arrows.

25 In the drawings, the reference numeral 2 indicates a foundation bed for the machine which is supported on any suitable table or bench. The foundation bed and table are cut away, as indicated at 4 and 4', to provide a space for a pinion gear 5. The member 2 is cut away, as indicated at 6, to provide a space for a pair of brackets 7 supporting a shaft 8 which carries the gear 5. Another bracket 9 supporting the free 30 end of the shaft 8 is secured to the table 3 by means of a pair of bolts 10. A handle 11 for turning the shaft 8, and the gear 5 secured thereto, is secured to the free end of the shaft in any suitable manner. It will be understood that the 35 shaft 8 may be driven by any suitable motor.

40 A guide channel 12 is disposed longitudinally of the foundation member 2. The guide channel is cut away, as indicated at 13, to register with the recesses 4 and 4' in the foundation member 45 and table. A slide member 14 fits within the guide channel 12. A rack 15 disposed centrally of the under surface of the slide member 14 has its teeth in engagement with the teeth on the pinion gear 5 so that rotation of the shaft 8 will 50 cause the slide member 14 to move longitudinally in the guide channel. The teeth of the rack stop short of one end of the rack to provide a stop member 16 which limits the outward movement of the rack. The upper edges of the slide member 14 are cut away, as indicated at 17, to pro-

vide a pair of flanges 18 of the same height as the inner side walls 19 of the guide channel. A pair of plate members 20, secured to the upper edges of the guide channel 12 by means of bolts 21, overlap the flanges 18 to prevent vertical movement of the slide member.

55 The slide member 14 is provided near one end with a stud 22 having its upper portion threaded, as indicated at 23, Figure 2. A turret 24 is rotatably mounted on the stud 22. The turret is retained on the stud by means of a nut 25 threaded to engage the threads 23. A washer 26 is positioned between the nut 25 and the turret. The turret is provided with a plurality of plungers 27

60 of various sizes. The turret may be rotated to selectively position any plunger in operative position. The plunger is maintained in operative position by means of a pin 28 fitted in a recess 29 in the under surface of the turret 24. A coiled spring 30 exerts constant force against the pin 70

28 to force it downwardly. The upper surface of the slide member 14 is provided with a plurality of shallow recesses 31 in which one end 75

of the pin 28 is adapted to fit. The number of recesses is the same as the number of plungers, 80 and the position of said recesses is such that whenever the pin 28 is positioned in any recess, one plunger is in operative position. The pressure of the spring 30 is slight enough so that the turret may be rotated to force the pin out of the 85 recess 31 and into another recess to position a different plunger in operative position after the nut 25 has been loosened slightly.

80 A trough shaped member 32 is secured in the channel member 12 in any suitable manner. The member 32 is adapted to support the back of a ring book. The book covers are supported by means of a pair of supports 33 mounted on suitable supporting structure 34. The trough shaped supporting member 32 is provided with 90

a front gage 35 and a back gage 36. The front gage is secured in place by means of a bolt 37. The front gage is provided with an aperture 38 through which the plunger 27 is adapted to be projected. The position of the back gage may 95 be adjusted to suit the length of the book being assembled. The back gage is secured in any desired position by means of the thumb screw 39.

100 The book parts to be assembled include a back plate 40 having integral tongues 41 bent up at right angles therefrom. The tongues 41 project through slots 42 in a spring plate 43. The spring plate has been previously assembled with a pair of toggle plates 44, a plurality of buttons 45 adapted to keep the inner edges of the toggle plates in 110

alignment, a plurality of divided ring members 46, and a cover plate 47.

A few turns on the handle 11 causes the plunger 27 to be projected through the aperture 38 in the 5 front gage member and into engagement with the tongues 41. The plunger forces the ends of the tongues down tightly against the spring plate 43 to hold the book parts together securely. Preferably the gages are adjusted so that the 10 plunger bends only one half the tongues against the spring plate. The book being assembled is then lifted from the trough and reinserted in reversed position so that the plunger may then force the rest of the tongues against the spring 15 plate. It is believed that the parts are more securely assembled when one half the tongues are bent in one direction, and the other half in the other direction.

It will be seen from the foregoing that I have 20 provided simple and efficient means for rapidly and securely assembling parts of ring books. If it is desired to operate on books differing in length from that for which the machine is set, it is necessary only to loosen the thumb screw 25 39, move the back gage to the required position and then tighten the thumb screw. If the size of metal is changed, the nut 25 is loosened slightly, the turret 24 rotated to align the proper plunger with the front gage, and the nut 25 tightened.

Although I have described a preferred embodiment of my invention in detail, it will be understood that the description thereof is illustrative rather than restrictive, as many details 35 may be modified or changed without departing from the spirit or scope of my invention. Accordingly, I do not desire to be restricted to the exact construction described, except as limited by the appended claims.

40 I claim:

1. In a ring book assembling machine, means for supporting the book parts to be assembled, a longitudinally movable slide member, a plunger projecting forwardly of said slide member and movable therewith to traverse a substantial portion of said supporting means, and means to guide said plunger into engagement with the book parts to be assembled.

2. In a ring book assembling machine, means 50 for supporting the book parts to be assembled, a guide channel terminating adjacent one end of said supporting means, a slide member movable in said channel, a plunger projecting forwardly of said slide member and movable therewith, said plunger engaging with the book parts to clinch tongues projecting from one book part through slots in another book part against said second mentioned book part.

3. In a ring book assembling machine, means

60

65

70

75

for supporting the book parts to be assembled, a guide channel having one end adjacent one end of said supporting means, a slide member movable in said channel, a turret mounted on said slide, a plurality of plungers of different sizes secured to said turret, said turret being adjustable to selectively cause one of said plungers to project forwardly of said slide member, said forwardly projecting plunger engaging with the book parts to clinch tongues projecting from one book part through slots in another book part against said second mentioned book part.

80

85

4. In a ring book assembling machine, means for supporting the book parts to be assembled with tongues extending from one book part through slots in another book part, means to selectively cause one plunger of a plurality of available plungers to engage said book parts to clinch said tongues against said second mentioned book part.

90

5. In a ring book assembling machine, means for supporting the book parts to be assembled, means to position the book parts on said supporting means, a plunger longitudinally movable across a portion of said supporting means, and means to guide said plunger into engagement with the book parts to be assembled.

100

6. In a ring book assembling machine, means for supporting the book parts to be assembled with tongues extending from one book part through slots in another book part, an adjustable 105 gage on said supporting means, and a plunger movable into engagement with said tongues to clinch said tongues against said second mentioned book part, said adjustable gage preventing sliding movement of said book parts during the movement of the plunger.

110

7. In a ring book assembling machine, means for supporting the book parts to be assembled with tongues extending from one book part through slots in another book part, a guide channel having one end adjacent said supporting means, a plunger mounted on a slide movable in said guide channel, and means at the end of said channel adjacent said supporting means for guiding said plunger into engagement with said book 115 parts to clinch said tongues against said second mentioned book part.

120

8. In a ring book assembling machine, means for supporting the book parts to be assembled, guide means adjacent one end of said supporting 125 means, a guide channel, a slide member movable in said guide channel, a turret mounted on said slide, and a plurality of plungers mounted on said turret, said turret being rotatable to selectively align said plungers with said guide means, the 130 plunger aligned with said guide means being movable through said guide means to engage the book parts to be assembled.
